WALTER S. LEVIN, OF SAN FRANCISCO, CALIFORNIA, ASSIGNOR TO NATIONAL SAFETY APPLIANCE COMPANY, OF SAN FRANCISCO, CALIFORNIA, A CORPORATION OF CALIFORNIA.

MAGNETIC-FIELD-CONTROLLING MEANS.

1,320,398.

Specification of Letters Patent.

Patented Nov. 4, 1919.

Application filed March 19, 1918. Serial No. 223,281.

To all whom it may concern:

Be it known that I, WALTER S. LEVIN, a citizen of the United States, residing at the city and county of San Francisco and State of California, have invented certain new and useful Improvements in Magnetic-Field-Controlling Means, of which the following is a specification.

The present invention relates primarily to the employment of a permanent magnet in the operation of signal, safety, or control means movable relatively thereto and preferably of a type carried by a train or other suitable movable body or object. The principal object of the invention is to control the keeper of the permanent magnet whereby said keeper will, when the magnet is inoperative connect the pole pieces thereof to prevent the demagnetizing thereof, and when it is desired to operate the signal, safety, or control means of the body moving relatively thereto to drop said keeper, to provide a sufficient air gap between the pole pieces thereof to insure the energizing of the movable member when the same passes in close proximity to said pole pieces and through the magnetic field of said magnet.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein,

Figure 1 is a diagrammatic plan view of the preferred embodiment of my invention illustrating the magnet, the controlling means therefor, and the track circuit for operating said controlling means.

Fig. 2 is a plan view of the magnet in position between the track rails and with the keeper in lowered position.

Fig. 3 is a sectional view taken on line 3-3 of Fig. 2.

Referring more particularly to the several views of the drawings, wherein like

characters of reference designate corresponding parts, the numerals 1 indicate suitable parallel track rails of the bonded type, the same being divided into sections or blocks through the insulating members 2. 60 Connected to one rail of each block are the respective leads 3 of a suitable track circuit having therein a source of electric energy 3' and leading from rails preferably at the opposite ends of said blocks are the 65 leads 4 connecting with a track relay 5.

Pivottally mounted in close proximity to the relay 5 is an armature 6, forming a part of a motor circuit 7, within which is a source of electric energy 8. The motor 70 circuit is adapted for the operation of a motor 9, to the armature 10 of which is connected a shaft 10', said shaft extending preferably beneath one of the rails at right angles thereto, and is mounted at its opposite end in a bearing 10² formed on a casting 11, which is positioned at one end of a suitable permanent magnet 12, formed preferably of laminations 13, said magnet being preferably of the bow or horse-shoe 80 type. Secured to the other end of the magnet 12, is a casting 14, similar to casting 11, said respective castings retaining the pole pieces 15 which are disposed upwardly preferably at right angles to the body portion of the magnet. To the casting 14, is pivotally connected to swing on a horizontal axis through the pin 16, a keeper 17, of sufficient length to bridge the poles of the magnet, said keeper being preferably 90 slotted as at 18 at its free end, and within said slot is positioned one end of a flexible member 19, which passes over an idler sheave 20, carried by an arm 21, on the casting 11, the opposite end of said member 19 95 being secured as at 22 to a winding sheave or drum 23 carried by the shaft 10'. The keeper 17 operates in a suitable casing 24 which precludes dirt or other foreign material from interfering with the dropping of 100 said keeper.

The operation of the present construction is as follows:

The shorting of the track circuit due to the passing of the train or car wheels 25, 105 into the block deenergizes the track relay 5 and permits the armature 6 to drop, at which time the weight of the keeper 17 unwinds the flexible member 19 from the drum 23 and causes a backing up of the motor 110

2
armature permitting the free end of the keeper 17 to drop sufficiently within the casing 24 to provide an air gap of sufficient distance between the free end thereof 5 and its coöperating pole piece. With the keeper in this position a movable member passing over the pole pieces 15, and within the magnetic field of the magnet will be energized sufficiently thereby to operate the 10 signal, safety, or controlling means connected therewith. On the passing of the wheels 25 from the block the track relay will be energized through the source of electric energy in the track circuit and will raise the 15 armature 6 completing the motor circuit, at which time the motor will be operated to wind the flexible connection 19 onto the sheave 23, and raise the keeper so that the same will connect the ends of said magnet.

20 While we have illustrated the keeper as being electrically operated, it is to be understood that the same may be operated by any other suitable form of mechanism if desired, just so long as the said keeper is moved 25 from the magnet to insure the said magnet energizing a suitable electric element when the same is moved within the field thereof, and to thereafter cause a movement of said keeper to connect the poles of said magnet 30 to insure the permanency thereof.

Having thus described my invention what I claim is:—

1. In combination with a magnet of the horseshoe type, a keeper coöperating with the poles thereof for bridging the same, and means for moving said keeper to provide an air gap between the same and its coöperating pole of a distance not less than the distance between the said poles.
- 40 2. In combination with a magnet of the horseshoe type, a keeper coöperating with the poles thereof for bridging the same, and means for moving said keeper to disconnect the same from one of said poles to 45 provide between the end thereof and said pole from which it is disconnected an air gap of a width not less than the distance between said magnet poles.
3. In combination with a magnet, a keeper 50 coöperating with the poles thereof for bridging the same, and electrically controlled means for operating said keeper to move the same to and from one of said magnet poles.
4. In combination with a magnet of the 55 horseshoe type, a keeper coöperating with the poles thereof for bridging the same and pivotally supported at one pole, and means coöperating with the free end of said keeper

for permitting movement of the same relatively to the other pole.

5. In combination with a magnet member of the shore-shoe type and a keeper member for bridging the poles thereof, one of said members movable relatively to the other, and means for moving said movable member to the other member to bridge the poles of the magnet and whereby said movable member is permitted to move by gravity from the other member to provide an air gap between the poles of said magnet.

6. In combination with a magnet of the horse-shoe type, a keeper pivotally mounted to one of the poles of said magnet to swing on a horizontal axis and adapted to contact with the other pole to bridge the same, means for raising the free end of said keeper to maintain the same longitudinally disposed in contact with its coöperating pole, said means capable of releasing to permit the lowering of the free end of said magnet 80 to provide an air gap between the free end thereof and its coöperating pole.

7. In combination with a magnet of the horse-shoe type, a keeper pivotally mounted at one end to one of the poles of said magnet to swing on a horizontal axis and adapted to contact with the other pole to bridge said poles, and means for moving the free end of said keeper relatively to its coöperating pole whereby said poles may be 90 either bridged or separated by an air gap between the free end of said keeper and its coöperating pole.

8. In combination with a magnet of the horse-shoe type, a keeper pivotally mounted 95 at one end to one of said magnet poles to swing on a horizontal axis, and adapted to contact with the other pole to bridge said poles, a flexible connection attached at one side to the free end of said keeper, a sheave 100 to which the other end of said connection is secured, said sheave capable of rotating in one direction for raising the free end of said keeper to bridge said magnet poles and capable of operating in another direction 105 due to the weight of said keeper to provide an air gap between the free end of the said keeper and its coöperating pole.

In testimony whereof I have signed my name to this specification in the presence 110 of two subscribing witnesses.

WALTER S. LEVIN.
